UNITED STATES PATENT OFFICE.

EUNICE M. ANTOONIAN, OF BOSTON, MASSACHUSETTS.

GARMENT.

Application filed August 4, 1924. Serial No. 729,897.

This invention pertains to garments, and more particularly to loose fitting, sleeved garments, such for example as bathrobes.

The usual mode of manufacture of such garments involves the cutting, by the aid of previously designed patterns, of a number of separate pieces from suitable material, and the subsequent assemblage of these pieces and their union by sewed seams.

10 In making garments intended to fit the person snugly, some such mode of procedure as that above outlined is apparently essential, but it has occurred to me that such a method is needlessly complicated and wasteful, both of material and labor, when applied to garments which are not designed nor intended to conform closely to the contour of the wearer.

I have accordingly devised a novel construction of garment and process of making the same, the principal object of my invention being to provide a garment of the class described, together with a process of making it, which may be manufactured 25 without appreciable waste of material and by relatively unskilled persons, unassisted by the use of previously designed patterns, but nevertheless when completed possessing all of the necessary and desirable utilitarian 30 characteristics of such a garment, and if desired, an ornamental and pleasing appearance.

In the accompanying drawings I have illustrated, by way of example, one preferred form of garment constructed in accordance with my invention, and also certain steps in the process of making the same.

In such drawings Fig. 1 is a front elevation of the completed garment.

40 Fig. 2 is a fragmentary rear view of the garment showing the position of the latter upon the person of the wearer, and Fig. 3 is a fragmentary view to smaller scale showing a piece of material from which the body of the garment may be constructed and indicating diagrammatically some of the steps in making the garment.

Referring to the drawings, and particularly to Fig. 3, the numeral 1 indicates 50 a piece of fabric of generally rectangular shape. This fabric may be a section cut from a length of piecegoods, manufactured by any of the usual textile processes, or may be an article of standard dimensions,

for example, a blanket, bath rug, or the like.

This piece of material has the upper edge 2, the lateral edges 3 and 4, and the bottom edge 5. Any, or all of these edges may be finished with an ornamental border 60 or fringe of any suitable character.

In making the garment this rectangular piece of fabric is first folded along longitudinal lines 6 and 7 to provide the front flaps 8 and 9, and the back 10.

65 Preferably, though not necessarily, the combined widths of the front flaps are substantially equal to the width of the back 10, so that when folded, the edges 3 and 4 lie adjacent to each other substantially along 70 the lines 3^a and 4^a, respectively, of Fig. 3. After folding, the upper edges 11 and 13 respectively of the flaps 8 and 9 are secured to the upper edge of the back 10 by means of seams 12 and 14 (Fig. 1) respectively.

75 Although the seams 12 and 14 have been described as separate seams, they may, and in fact, ordinarily would, constitute portions of a continuous seam extending across the entire width of the back. While sewed 80 seams form a desirable form of connection between the parts, it is contemplated that other and equivalent means of securing the parts together may be employed, if desired.

Slits 15 and 16 are formed either after 85 or before the formation of the seams 12 and 14 along the upper portions of the fold lines 6 and 7, respectively, such slits constituting armholes for the reception of sleeves 17 and 18, respectively.

90 These sleeves may be made in any desired manner from suitable material, either like that of the body portion of the garment, or otherwise, if desired, and are connected to the body of the garment by seams 95 19 and 20, extending completely around the armholes. For certain types of garment it may be found desirable to omit the sleeves, the edges of the armholes being suitably bound or otherwise finished to provide a 100 smooth edge. Moreover, it is contemplated that under some circumstances, the slits forming the armholes may also be omitted.

105 During the formation of the seams 12 and 14, or thereafter as may be preferred, a hood or cowl 21 is preferably though not necessarily attached to the upper edge of the back 10. This hood or cowl may be

made in any usual manner, from the same material, or different material, as the other parts of the garment, and may, if desired, be provided with an ornamental border or 5 fringe 22.

While in accordance with the preferred construction, the body of the garment, including the back 10 and the front flaps 8 and 9, is formed integrally from a single 10 piece of material, the invention contemplates in its broadest aspects the making of the front flaps 8 and 9 as separate parts secured along lines corresponding to the fold lines 6 and 7 to the lateral edges of the back member 10. Such construction may be found 15 useful when the dimensions of the garment are such that it is difficult to secure a single piece of material of a width sufficient to permit its margins to be folded in to form the 20 side flaps, and also adapts itself to the construction of garments whose front flaps are of a different material from the back. Regardless of the manner in which the back and front flaps are united, the adjacent edges 25 3 and 4 of the front flaps are left free from each other throughout their entire lengths, and these edges are united to the back only at their upper ends.

In donning the garment the wearer 30 spreads the front flaps apart and slips his arms into the sleeves, drawing the front flaps about his person and securing them if desired, by means of a belt, buttons, or other fasteners, not shown. When the garment 35 is thus disposed about the person of the wearer his neck occupies the upper part of the space between the adjacent edges 3 and 4 of the front flaps 8 and 9, the upper parts of which extend over his shoulders, as indicated in Fig. 2.

This construction avoids the necessity of providing a shaped opening for the wearer's neck, and thus eliminates the cutting and fitting usually required in making a garment of this type.

I claim:

1. That process of making garments which comprises folding in the lateral marginal portions of a piece of fabric of suitable dimensions until their free lateral edges substantially meet, uniting, as by stitching, one end of each of said lateral marginal portions to the adjacent end margin of the central part of the fabric; and attaching a sleeve at a point adjacent to each fold line.
2. That process of making garments which comprises folding a piece of fabric to provide a back and a pair of front flaps, stitching a portion of the upper edges of the front flaps directly to the upper edge of the back, slitting the fabric along the upper parts of

the fold lines defining the junction of the back with the respective front flaps to provide armscyes, and seaming a sleeve in each armseye.

3. That process of making garments which comprises folding in the marginal portions of a substantially rectangular piece of fabric so as to bring the lateral edges of the fabric into juxtaposition, thereby producing a pair 70 of front flaps of a combined width substantially equal to the width of the central portion constituting the back of the garment, sewing the outer portion of the upper edges of the front flaps directly to the back, and 75 attaching sleeves along the junction of the back with the respective front flaps.

4. That process of making garments which comprises as steps providing a substantially rectangular back and a pair of front flaps, 80 the latter having a combined width substantially equal to that of the back, seaming the upper edges of the front flaps directly to the upper edge of the back throughout the length thereof, and attaching sleeves along 85 the junction of the back with the lateral margins of the respective front flaps.

5. A garment comprising a substantially rectangular piece of fabric folded longitudinally to provide a back and a pair of front 90 flaps, seams uniting the upper ends of the front flaps to the upper edge of the back, said flaps being free from top to bottom along their opposed lateral edges, a sleeve secured in a slit extending along each line 95 of fold, and a hood seamed to the upper edge of the back.

6. A garment comprising a substantially rectangular piece of fabric folded along parallel lines to provide a back and a pair 100 of front flaps, the latter having a combined width substantially equal to that of the back, the adjacent longitudinal edges of said flaps being free from each other from top to bottom, seams uniting the upper ends of the 105 flaps directly to the upper edges of the back, and a sleeve seamed in a slit extending along the upper part of each fold line.

7. A garment comprising a substantially rectangular piece of fabric constituting a 110 back, front flaps united along their lateral edges to the lateral edges of the back, said front flaps being free to open from top to bottom and having their upper edges seamed to the upper edge of the back, and sleeves inserted in the upper parts of the lines of union of the respective front flaps to the back.

Signed by me at Boston, Massachusetts, this twentieth day of June, 1924.

EUNICE M. ANTOONIAN.
